UNITED STATES PATENT OFFICE.

RICHARD B. WAGONER, OF ALBANY, NEW YORK.

MILK-BOTTLE SAFE.

1,324,531.

Specification of Letters Patent.

Patented Dec. 9, 1919.

Application filed September 13, 1918. Serial No. 253,928.

To all whom it may concern:

Be it known that I, RICHARD B. WAGONER, a citizen of the United States, residing at Albany, in the county of Albany and State 5 of New York, have invented certain new and useful Improvements in Milk-Bottle Safes, of which the following is a specification.

This invention relates to deposit and collection receptacles and more especially to 10 those intended for milk and other domestic commodities which are usually left at the door early in the morning.

The object of the invention is to produce a 15 safe having compartments in which milk bottles and the like may be left, the door to each compartment being locked by the weight of the milk bottle when dropped into the safe, whereby it is necessary for 20 the housewife to come later and open the entire cover of the receptacle in order to get the bottle or bottles.

This object and other objects are carried 25 out by the construction described in the following specification, set forth in the claims, and shown in the drawings, wherein:

Figure 1 is a vertical section through a milk bottle safe of this character having two compartments, one compartment here 30 being shown as empty and the other as containing a bottle,

Fig. 2 is a vertical section on the line 2—2 of Fig. 1,

Fig. 3 is a plan view of the complete safe. 35 The numeral 1 designates a box-like body, preferably of metal and of proper size and finish so that it shall be an object of ornament to the porch rather than otherwise. To this end it may be appropriately painted 40 and perhaps ornamented. It is secured to a post or perhaps against a wall alongside the kitchen door or elsewhere within convenient and easy access of the housewife in the morning. It has a cover 2 hinged at the 45 back as at 3 and adapted to be fastened with a hasp 4 and padlock 5, or other suitable lock whereof the key is held only by the housewife. In said cover in the present 50 case are formed two openings 6 of ample size to admit the insertion of an ordinary milk bottle as designated by the

letter B, and each opening is closed by a trap door 7 connected with the underside of the cover at the outer edge of the door by a spring hinge 8 whose normal tendency 55 is to throw the door upward against the cover and therefore close the opening 6.

Transversely across the interior of the body and beneath the mid-length of the cover is secured at the top of the body a 60 narrow cleat 10, and directly beneath it and at the bottom of the body is secured a relatively wider cleat 11. The body is thus divided into two sides or halves, and in each half is a rocking element constituting a 65 right-angular pocket. Each is shown herein as having an upright back 12, a strictly horizontal foot 13, and triangular side wings 14 connecting these members, and upon each foot may be secured a cushion 70 15. Also another cushion may be secured to the side wall of the body in position to be struck by each trap door 7 when swung open, this last cushion being numbered 17. A contractile spring 18 draws the back 75 walls of the pockets toward each other and into contact with opposite faces of the two cleats.

The action of this device is now as follows: Normally each pocket stands in the 80 position occupied by that at the left of Fig. 1, with the upper and lower ends of its back 12 against both cleats and the outer end of its foot 13 raised off the bottom of the receptacle or body. This follows because 85 the pocket is strictly right angular, whereas the space for the pocket is not quite right angular because of the difference in width of the two cleats. Now when the milkman comes and drops a bottle B through the 90 trap door 7, the latter is swing forcibly open against the tension of the spring hinge 8, possibly flying back against the cushion 17, and the bottle falls onto the cushion 15 as seen at the right of Fig. 1. The weight 95 of the filled bottle now bears the foot 13 down flat onto the bottom of the body, with the result that the upright portion or back 12 is swung inward to a slight extent and stands vertical as seen at the right of Fig. 100 1, rather than oblique as seen at the left in Fig. 1. This brings the upper end of the

back under the free edge of the trap door and prevents an unauthorized person or in fact any person from pushing down on the trap door, so long as the parts remain as shown and described. The result is that the only means of access to the interior is through the opening of the cover, and this cannot occur until the lock 5 is unlocked by the proper person. Thus the weight of the 10 bottle is used to swing the upright member of the right-angular pocket beneath the free edge of the trap door, and in effect it locks this door against being opened until the entire cover 2 is raised and the bottle 15 removed. The parts immediately then resume the position shown at the left of Fig. 1 by reason of the contractile spring 18.

What is claimed as new is:—

1. In a deposit and collection receptacle, 20 the combination with a rectangular body whose top has a pair of openings, trap doors independently closing said openings, spring hinges holding them normally closed, and a cushion for each door within the body; 25 of a cleat across the interior of the body just under said top, a second cleat across the interior of the body at the bottom thereof, a pair of right-angular pockets having upright backs standing next each other and 30 feet projecting away from each other, cushions on said feet, and a contractile spring connecting the backs and drawing them normally against both cleats, substantially as described.

35 2. In a deposit and collection receptacle, the combination with the body having an opening in its top, and a door closing said opening from the interior of the body and mounted on a spring hinge; of a right-angular 40 pocket disposed within said body and including an upright back, a foot, and side wings connecting these parts, a cleat on the bottom of said body defining a fulcrum point for the angle between said back and 45 foot, and yielding means drawing the upper end of said back normally out from under the free end of said door but permitting its movement beneath said free end under the influence of the weight of an article resting 50 on said foot.

3. In a deposit and collection receptacle, 55 the combination with the body having an opening in its top, and a door closing said opening from the interior of the body and mounted on a spring hinge; of a right-angular 60 pocket disposed within said body and including an upright back, a foot, and side wings connecting these parts, a cleat on the bottom of said body defining a fulcrum point for the angle between said back and 65 foot, a second cleat beneath the cover of said body, and a spring drawing the back of said pocket normally against both cleats, substantially as described.

70 to move away from said last-named cleat 65 under the influence of the weight of an article resting on said foot.

4. In a deposit and collection receptacle, 75 the combination with a rectangular body, a hinged cover therefor having a pair of openings, trap doors independently closing said openings, spring hinges at the outer edges of said doors holding them normally closed, and a lock for securing said cover to the body; of a narrow strip across the interior 80 of the body just under said cover, a wider strip across the interior of the body at the bottom thereof, right angular pockets within the body with their backs next each other and their feet projecting away from each other, and a contractile spring connecting said backs and holding their upper edges normally against said narrow strip and their feet normally raised off the bottom of the body, the whole for use substantially as 85 described.

5. In a deposit and collection receptacle, 90 the combination with a rectangular body, a hinged cover therefor having a pair of openings, trap doors independently closing said 95 openings, spring hinges at the outer edges of said doors holding them normally closed, and a lock for securing said cover to the body; of a narrow strip across the interior of the body just under said cover, a wider strip across the interior of the body at the bottom thereof, a pair of right-angular 100 pockets having upright backs standing next each other, right-angular feet projecting away from each other, and side wings connecting the other parts, cushions on said feet, and a contractile spring connecting the backs, the tension of the spring being such as to hold the upper ends of said backs normally out from under the free edges of the 105 trap doors but to permit their movement thereunder when impelled by the weight of a milk bottle on the foot, substantially as described.

6. In a deposit and collection receptacle, 110 the combination with a body whose top has a pair of openings, trap doors independently closing said openings, spring hinges normally holding them closed, of a cleat across the interior of the body just under said top, 115 a second cleat across the interior of the body at the bottom thereof, a pair of right angular pockets having upright backs standing next each other and a contractile spring connecting the backs and drawing them normally against both cleats, substantially as 120 described.

7. In a deposit and collection receptacle, 125 the combination with a body whose top has a pair of openings, trap doors independently closing said openings, spring means holding them normally closed, of abutment means across the interior of the body just

under said top, abutment means across the interior of the body at the bottom thereof, a pair of right angular pockets having upright backs standing next each other and 5 feet projecting away from each other, and a contractile spring connecting the backs and drawing them normally against both

abutment means, substantially as described.

In testimony whereof I affix my signature in presence of two witnesses.

RICHARD B. WAGONER.
